US0D1025036S

(12) **United States Design Patent** (10) Patent No.: **US D1,025,036 S**
(45) Date of Patent: ** Apr. 30, 2024

(54) **SINGLE-PORT OMNIDIRECTIONAL ANTENNA**

(71) Applicant: **Impinj, Inc.**, Seattle, WA (US)

(72) Inventors: **Pavel Nikitin**, Seattle, WA (US);
Venkata S. Kodukula, Bothell, WA (US); **John Franklin Kim**, Bothell, WA (US)

(73) Assignee: **Impinj, Inc.**, Seattle, WA (US)

(**) Term: **15 Years**

(21) Appl. No.: **29/884,094**

(22) Filed: **Feb. 7, 2023**

(51) LOC (14) Cl. **14-03**

(52) U.S. Cl.

USPC **D14/230**

(58) **Field of Classification Search**

USPC D14/230, 231–240, 203–229, 138, 358;
D12/42–43

CPC H01Q 1/12; H01Q 1/00; H01Q 1/088;
